(57) **CLAIM**

The ornamental design for a pill box, as shown and described.

DESCRIPTION

FIG. 1 is a front view of a pill box showing my new design. FIG. 2 is a back view of the pill box shown in FIG. 1. FIG. 3 is a side view of the pill box shown in FIG. 1; and, FIG. 4 is a top view of the pill box shown in FIG. 1. The left and right side views of the pill box are a mirror image. The top and bottom views are plain and unornamented.
